SELECTIVE SYSTEM FOR USE WITH THIN STRIPS OR SHEETS OF PAPER AND METHOD OF USING THE SAME

Fred S. Crane, Euclid, Ohio

Application October 8, 1947, Serial No. 778,616

5 Claims. (Cl. 129—16.1)

1

My invention relates to a selective system for use with thin strips or sheets of paper and to methods of using the same, and it is a primary object of the invention to provide methods for preparing commercial papers, also called account papers, so that they can be sorted by the use of a needle. Such papers are made of paper stock, by which I mean light weight paper stock such as is used for bank checks, deposit slips, accounting machine paper in general, and other like papers used in accounting and merchandising and the like, as distinguished from card stock, cardboard and other stiffer and heavier paper stocks. Such papers must be sorted by the aid of gravity, as they cannot be propelled by power like cards, because of their flexibility. They should also have smooth unbroken margins all around the sheet to prevent difficulty in their use in the various types of check-writers, check-endorsers, check-cancelling machines, addressing machines, etc.

Another object is to provide a novel field of perforations for setting up a code.

Another object of the invention is to provide a novel code for use in selective systems of the character described.

Another object of the invention is to provide means for making a preliminary digit sort in a code set up for numerical sorting.

Another object is to provide means for sorting a stack of checks or like paper articles while keeping all the members of the stack under control, or with a minimum of displacement of members of the stack aside from that movement necessary for completion of a sorting step.

Another object is to provide means for facilitating the separation of a stack of thin paper members into two completely separated portions after a preliminary step whereby certain members have been partly separated from the remaining members of the stack.

Another object is to provide improved dividers for a mass of checks or the like, whereby a rough division may be preserved in a pack or system of checks or the like in which individual members are liable to be frequently removed and returned to the mass, thus preserving the members more or less in sequence.

Other objects and advantages of the invention will appear upon consideration of the following specification, and of the annexed drawings, which are made a part of this application and in which similar reference characters indicate similar parts. In the drawings:

Fig. 1 is an elevation of a stack of sheets, such as

as checks or deposit slips or the like, partly broken away, and viewed from the front,

Fig. 2, an elevation of portions of each of a series of such sheets, showing in each portion one of the columns of perforations of the code of my invention, and also showing how the perforations may be connected in pairs by removal of the intervening material, so as to form slots for selecting operations, by indicating in the column any one of the nine digits of the Arabic system of notation, as for use in a selective system,

Fig. 3, a face view of a check, showing the relative positions of the printed matter and of the features of my invention,

Fig. 4, a similar view of a deposit slip,

Fig. 5, a view of a stack member having a slot in the tens column; and

Fig. 6, a detail of another stack member.

20 The system of my invention comprises sheets indicated generally by reference character 10, which may be arranged in a stack, as indicated in Fig. 1, and which are intended for sorting by means of a needle 11. Preferably the sorting is done by merely holding a stack of cards in the hand, so that all cards can be kept under immediate manual control, but that is not essential.

25 The sheets are each provided with a field consisting ordinarily of holes 12 arranged in parallel vertical rows when the stack is held in position for a sorting operation, i. e., the holes are in columns or rows standing at right-angles to the adjacent margin of the respective sheets, and there are six holes in each column. Preferably there are six such parallel columns and the holes are about one-fourth inch apart vertically and laterally, thus making a field about two inches square, or small enough to be easily formed between the sides of a check of ordinary size. It

30 35 40 45 50 will be understood that the field may be located at either end of a check or like commercial paper. Such an arrangement of the field eliminates all need for marginal notches and perforations, and makes it possible to set up a code for a large variety of selections, all in very small space and in compact arrangement, in place of the arrangement of fields about several or all the margins of a sheet or card. While the holes are herein referred to as being punched, they may obviously be made in other ways, and even may be provided in the sheets when being made from stock.

To provide a code that shall take care of all nine digits in one column without making any slots longer than the space of two original per-

2

forations I have devised a novel code, which can of course also be used in the columns for tens, hundreds, etc., in a decimal system of notation. According to this code the absence of slots indicates zero, and a slot 13 is punched between the uppermost hole and the next one below in the units column, as shown in Fig. 2, for selection of a card indicated by a digit "1," or by a number whose last digit is "1"; a slot 14 is punched out or otherwise provided between the second hole and the third in the column for a final digit "2"; a slot is punched at 15 between the third hole and the fourth for numbers ending in "3"; slots are punched at 16 and 17 for digit "4" (i. e., "1" plus "3"); a slot is punched at 18 for digit "5"; slots at 19 and 20 for digit "6" (i. e., "1" plus "5"); slots at 21 and 22 for digit 7 (i. e., "2" plus "5"); slots at 23 and 24 for digit "8" (i. e., "3" and "5"); and "slots" at 25, 26 and 27 for digit "9" (i. e., "1" plus "3" plus "5"). The space between the fourth and fifth holes in the column (i. e., the fourth space from the top of a column) is never slotted.

An important advantage of the code described is that it is never necessary to connect more than two holes in punching out the intervals for a numerical system, and the same can be made to apply to other systems, as hereinafter described. When more than two holes are connected into a slot it is very difficult to avoid the formation of shoulders at the intermediate hole, such as are liable to cause sheets to hang up on the needle in sorting, and so delay the work or cause errors in the same. See Fig. 6, where a part of a check is shown that is slotted through four holes in the units column, and where shoulders are left at one of the intermediate holes that would hang on a needle. Another advantage over other codes is that only four insertions of a needle are required for a complete operation of sorting paper according to the indications in the final numeral column of the sheets of the stack under treatment, and four insertions for other columns, as described below.

Each sheet is provided between the field of perforations and the end of the sheet next above the field when the sheet is held with that end up which is nearest the field, with a vision and lifting hole 28 that is preferably larger than the perforations 12 and which is located above the middle of the sheet so that a needle may be inserted through hole 28 and the sheet will hang down from the needle and be balanced evenly like a pendulum. The thin sheets that are used as commercial paper are much less adapted for needle sorting than cards, both because of their lighter weight individually and because of greater adhesion between sheets due to greater tendency toward the exclusion of air from the intermediate spaces.

Another use for the hole is as a vision hole to make sure, before withdrawing the sorting needle from the stack during a sorting operation, that all the selected sheets have made their proper drop. As a third function for the vision and lifting hole one may take sorted checks or packages of sorted checks and the like commercial paper and hang them on a rod or hook, or can place them on such a device and add thereafter a device to prevent removal. Such a procedure can save tons of rubber bands per day if generally adopted. Or, of course, checks so provided with a hole at top center (preferably oversized) can very conveniently be fastened together by split metal fasteners or other fasteners, as for storage by a customer of a bank. The top central location is

of advantage over other locations for holes otherwise having registering perforations for all these uses and for sorting cards and the like, but especially for sorting thin paper sheets.

5 All the sheets have an upper left hand corner removed as at 29, this being for the purpose of preliminary determination as to whether any sheets are facing the wrong way or are wrong end up. When a stack has been assembled, any 10 sheet that is so misplaced will show a solid portion at the upper left-hand corner and can be taken out and positioned correctly.

Another way of determining whether all sheets 15 face in the same direction and are right end up is by the use of registering holes at the upper right-hand corner, as at 30, through which the sorting needle may be passed if they are all in proper position; but if any check is bottom end up or facing in the wrong direction the needle 20 cannot pass it.

Dividers of smooth card stock may be provided, 25 such as that shown at 31. These dividers will have two square upper corners, with a perforation at 32, at the upper left corner, and otherwise may be perforated as those of the sheets 10, with field perforations 12', a slot 14' indicating "20," lifting and vision holes 28' and a testing hole 30', all as shown in Fig. 5. By means of the holes 32 all the dividers can be removed, e. g., prior to 30 selection of the sheets. The fields are mechanically cut to indicate 10—20—30—40, etc., as a convenience in replacing sheets that have been removed or are to be added to the mass of cards.

Fig. 4 illustrates a deposit slip such as can be 35 used to good advantage with the checks that have been perforated and slotted in accordance with my described invention. In that figure the slip is indicated by 33, it has a vision and lifting hole 34, a corner removed at 35, a testing hole 36, and a space at the lower left-hand corner with a line at 37 for the signature of the depositor.

While features of my invention may be used in 40 various fields and for various purposes the main utility at present contemplated is banking. For the past twenty-five years, the American Banking 45 Association, the U. S. Bureau of Standards and other private and U. S. Government organizations have recognized the advantages of using bank checks of standardized size, for the saving of time and money.

Each party having a checking account at a 50 bank is first provided with a supply of checks and deposit slips in which each check and deposit slip is provided with a field of perforations slotted so as to indicate the same master number.

Now let it be assumed that a bank has a pack 55 of checks bearing account numbers ranging from 1 to 999. First, they are to be stacked evenly with the "field" at the left. Holding them lengthwise 60 in the left hand with the "field" at the top, insert the sorting needle through the pack at the second hole in the extreme right hand or "units" column. Releasing the hold with the left hand permits all 65 checks containing a "cne" slot in that digit to drop until stopped by the needle encountering the top of the slot, or approximately one-fourth inch. Now, before removing the sorting needle, look 70 through the combination vision and lifting hole which is located above the "field." If clear vision is afforded through the entire pack it shows 100% drop of the selected checks. Hold the pack in the left hand and remove the needle from the sorting hole and insert it into the lifting hole. The selected checks will now be permitted to drop entirely from the pack but are kept in control and

in vertical position in the left hand. Take the lifted checks and place them in front of the selected checks; bring the edges of the pack into alignment again and we are ready to proceed with the sorting operation.

Repeat the same process described above, this time inserting the needle through the third hole in the "units" column, sighting through the vision-lifting hole, lifting the checks, catching the selected checks and placing the lifted checks at the front of the pack. Repeat again in the fourth hole, and then again, this time skipping the fifth hole and using the sixth hole.

When this process has been completed in the "units," proceed to the next row to the left of the "units" column, this being the "tens" column and repeat. The same process is done in the third from right or "hundreds" column, and after these twelve needle insertions, the pack will be accurately sorted from 1 to 99, the numbers starting on top of the stack and proceeding to 999 on the bottom.

The fourth column of holes from the right is for preliminary digit sorting. Banking is all based on the clearing-house hour of 10:30 A. M. each day. Therefore, in order to handle a big volume today it may be necessary to have perhaps a dozen people start in to sort thousands of checks. By the use of the first slot in the fourth column (which may be formed in desired checks as indicated in dotted lines in Fig. 3), I drop all of the accounts between 1 and 9 as these are the utility, telephone, and electric light people who have volume. The second slot drops out all accounts numbered from 10 to 99, and the third drops out the accounts numbered from 100 to 999. My special code, described above, is so designed that I can now take each of the three packs of checks obtained through my preliminary digit sort just described, and by inserting the needle once in the "five" slot of each digit, split each package into two groups of cards, one group including cards punched in the fourth column to indicate final digits 0 to 4, and the other group to indicate final digits 5 to 9 dropping out, and the 0-4 remaining on the needle. This can be further carried out in the hundreds column by sorting them from 100-900, thereby making packages containing checks for accounts numbered 100-200; 200-300; etc. When this is completed everyone can go to work on his package, and when they all finish the numerical sequence of all the checks will be uninterrupted. This eliminates all sorting bottle-necks.

When the deposit slips are included in the same mass with the checks to be sorted they are first placed at the back (bottom) of the pack of checks. The whole mass is then sorted in the usual way and when the sorting operation is finished the deposit slips for each individual account will be found next to and immediately following the checks for that account. This eliminates the present practice wherein the bookkeeper must watch two piles (checks and deposit slips) at the same time to compare signatures, causing much eyestrain and resulting in errors. This system puts all the signatures in one spot and simplifies the work of checking the signatures on checks and deposit slips. Checks and deposit slips are then filed by the bank in the same drawer until the end of the month. When it comes time to send the depositor his cancelled checks, the deposit slips are needed out in one operation by providing one slot 38 in the fourth column (after the ones used for digit break-down); then the

checks are mailed and the deposit slips filed away.

As can be seen from the above description, three sorting columns provide sorting of accounts numbered from 1 to 999. In order to provide about 25,000 different account numbers, I propose to prefix each number with a letter of the alphabet indicating the letter with which the customer spells his surname; thus there will be numbers A-1 to A-999, B-1 to B-999 etc. through the alphabet, making about 25,000. In order to accomplish this and to sort them I have invented an alphabetical sorting system used in combination with figures. The sorting of figures has been described above, and I will now describe how the letters of the alphabet are first sorted before proceeding with the numerical sort. In the event of smaller volume of work, of course, the numerical sort may be made first and the alphabetical break-down sorted after the account numbers have been placed in sequence.

The fifth and sixth columns of holes from the right provide the necessary slots for alphabetical sorting. My simplified alphabetical assigning is accomplished by simply prefixing the letter "A" to 999 different numbers for all surnames, beginning with "A," etc. for each letter of the alphabet regardless of the spelling of the name and regardless of how many have the same name. The alphabet is broken down into five divisions of five letters each (y-z being considered one letter) as follows:

1st division, a, b, c, d, e
2nd division, f, g, h, i, j
3rd division, k, l, m, n, o
4th division, p, q, r, s, t
5th division, u, v, w, x, y-z

The individual checks and deposit slips, in the 40 fifth column, which is used to segregate the five divisions of the alphabet are provided with slots in five different positions to indicate the five divisions. The five divisions are needed and dropped out of the pack one at a time, and kept 45 separate from the pack. This is accomplished by needle insertions in the second, third, fourth, fifth, and sixth holes.

The individual checks and deposit slips, in the sixth column, are provided with slots in five 50 different positions, and are used to select individual letters of the alphabet. Sorting each pack containing a division of the alphabet separately, the first slot (second hole) was used to select the first letters of the division being 55 sorted, that is A, for the first division, F for the second, K for the third, P for the fourth, and U for the fifth division. Using the second slot (third hole) the second letter of a division can be selected, B, G, L, Q, or V, depending on which 60 division is being sorted. It can readily be seen how this sixth column selects individual letters after the alphabet has been divided into the five sections by use of the fifth sorting row.

For some purposes, it may be desirable to add 65 perforations to a vertical column, through six holes in a row with a pattern of slots anywhere except in the fourth space from the top is a characteristic of my special code, and is a highly desirable arrangement. Obviously, also, the number of vertical columns may be increased when it is desired to classify cards according to other items than those above described.

The "top" of a row, as the term is used herein, is that end of the row which is uppermost during a selecting operation; usually the end nearest

to a margin of the sheet, though not always or necessarily so.

The small field required for my special code in the case of bank checks, deposit slips and similar commercial paper is of advantage in that it may be placed at one end of such a paper where it will be out of the way of the body of the check where significant data occurs. At the same time, the perforations forming the field do not interfere with printing of immaterial matter between the lines of perforations.

It will be obvious to those skilled in the art that many variations may be made in the system and methods of operation herein disclosed, all without departing from the spirit of the invention; and, therefore, I do not limit myself to what is shown in the drawings and described in the specification, but only as indicated in the appended claims. As an instance of such a variation, the slots described as being formed in the fifth and sixth columns could be in other columns, if available, and they could be distributed over more than two columns if that were thought desirable for any reason.

This is a continuation in part of my application, Ser. No. 611,191, filed August 17, 1945, for patent on Sheets and the like for sequence sorting.

Having thus fully described my invention, what I claim is:

1. A sheet for classification purposes having a row of six perforations, the perforations in the row being united in pairs to form elongated slots according to a code in which the first of a series of successive members is indicated by a slot connecting the first and second holes in a row; the second, by a slot connecting the second and third holes; the third, by a slot connecting the third and fourth holes; the fourth, by slots respectively connecting the first and second and the third and fourth holes; the fifth, by a slot connecting the fifth and sixth holes; the sixth, by slots respectively connecting the first and second and the fifth and sixth holes; the seventh, by slots respectively connecting the second and third and the fifth and sixth holes; the eighth, by slots respectively connecting the third and fourth and the fifth and sixth holes; and the ninth, by slots respectively connecting the first and second, the third and fourth and the fifth and sixth holes.

2. A sheet for classification purposes having a field of perforations arranged in parallel rows each including six perforations, the perforations of a row being united in pairs to form elongated slots according to a numerical code in which zero is indicated by absence of such slots; numeral one by a slot connecting the first and second holes; numeral two by a slot connecting the second and third holes; numeral three by a slot connecting the third and fourth holes; numeral four, by slots respectively connecting the first and second holes and the third and fourth holes; numeral five, by a slot connecting the fifth and sixth holes; numeral six, by slots respectively connecting the first and second and the fifth and sixth holes; numeral seven, by slots respectively connecting the second and third and the fifth and sixth holes; numeral eight, by slots respectively connecting the third and fourth and the fifth and sixth holes; and numeral nine, by slots respectively connecting the first and second, the third and fourth and the fifth and sixth holes.

3. A stack of sheets for classification purposes, said stack including division sheets interposed between parts of the stack, each of the sheets of the

stack having a row of six perforations so located as to register with homologous perforations in the other sheets; the perforations in a row being united in pairs to form elongated slots according to a code in which the first of a series of successive members is indicated by a slot connecting the first and second holes in a row, the second by a slot connecting the second and third holes, the third by a slot connecting the third and fourth holes, the fourth by slots respectively connecting the first and second and the third and fourth holes, the fifth by a slot connecting the fifth and sixth holes, the sixth by slots respectively connecting the first and second and the fifth and sixth holes, the seventh by slots respectively connecting the second and third and the fifth and sixth holes, the eighth by slots respectively connecting the third and fourth and the fifth and sixth holes and the ninth by slots respectively connecting the first and second, the third and fourth and the fifth and sixth holes; the division sheets each having homologous perforations in an upper corner, and the other sheets having the corresponding corner removed to permit simultaneous engagement of all the division sheets by a sorting needle without engaging the other sheets.

4. A stack of sheets for classification purposes, said stack including checks and deposit slips, of like size and shape, each of the sheets of the stack having a row of six perforations so located as to register with homologous perforations in the other sheets; the perforations in a row being united in pairs to form elongated slots according to a code in which the first of a series of successive members is indicated by a slot connecting the first and second holes in a row, the second by a slot connecting the second and third holes, the third by a slot connecting the third and fourth holes, the fourth by slots respectively connecting the first and second and the third and fourth holes, the fifth by a slot connecting the fifth and sixth holes, the sixth by slots respectively connecting the first and second and the fifth and sixth holes, the seventh by slots respectively connecting the second and third and the fifth and sixth holes, the eighth by slots respectively connecting the third and fourth and the fifth and sixth holes and the ninth by slots respectively connecting the first and second, the third and fourth and the fifth and sixth holes; the deposit slips being similar to the checks in size and shape and each having a signature line positioned to locate the depositor's signature on a deposit slip in similar position to his signature on a check.

5. A method of sorting a stack of classification sheets consisting of checks and deposit slips of like size and shape so as to arrange them in sequence with each depositor's checks in a group and with his deposit slips in a group immediately adjacent to his group of checks, said method comprising a first step of providing each classification sheet with a row of six perforations, so located as to register with homologous perforations in each of the other sheets, then uniting the perforations of the sheets in pairs according to a code in which the first of a series of successive members is indicated by a slot connecting the first and second holes in a row, the second by a slot connecting the third and fourth holes, the third by a slot connecting the third and fourth holes, the fourth by slots respectively connecting the first and second and the third and fourth holes, the fifth by a slot connecting the fifth and sixth holes, the sixth by slots respectively connecting the first and second and the fifth and sixth holes, the seventh by slots respectively connecting the second and third and the fifth and sixth holes, the eighth by slots respectively connecting the third and fourth and the fifth and sixth holes and the ninth by slots respectively connecting the first and second, the third and fourth and the fifth and sixth holes.

and second and the fifth and sixth holes, the seventh by slots respectively connecting the second and third and the fifth and sixth holes, the eighth by slots respectively connecting the third and fourth and the fifth and sixth holes, the ninth by slots respectively connecting the first and second, the third and fourth and the fifth and sixth holes; then separating the checks from the deposit slips; then placing the stack of deposit slips back of the stack of checks; and then needle 10 sorting the combined stacks.
